UNITED STATES PATENT OFFICE

WILLIAM J. CAMPBELL, OF INDIANAPOLIS, INDIANA, ASSIGNOR TO AMERICAN SLICING MACHINE COMPANY, OF CHICAGO, ILLINOIS, A CORPORATION OF NEW YORK

SLICING MACHINE

Application filed June 11, 1928. Serial No. 284,293.

My invention relates to a slicing machine of the type wherein a circular knife is employed, herein shown as motor driven. One object of the invention is the provision of means for protecting the fingers of the operator from the knife. Another object is the provision of means for completing, enclosing or shielding the cutting edge from the rear or slice discharge side. Other objects will appear from time to time in the course of the specification and claims.

I illustrate my invention more or less diagrammatically in the accompanying drawings, wherein—

- 15 Figure 1 is a horizontal section;
- Figure 2 is a rear elevation;
- Figure 3 is a fragmental horizontal section illustrating a variant form of adjustable gauge plate;
- 20 Figure 4 is a section on the line 4—4 of Figure 2;
- Figure 5 is a front elevation of a modification;
- Figure 6 is a section on the line 6—6 of Figure 5; and
- 25 Figure 7 is a section on the line 7—7 of Figure 5.

Like parts are indicated by like symbols throughout the specification and drawings.

- 30 A indicates any suitable base member upon which is mounted the motor A¹ with the motor shaft A² and the pulley A³ about which passes the belt A⁴.

B generally indicates the rotary knife on the knife shaft B¹, associated with which is a pulley B² about which passes the belt A⁴.

- 35 The front of the knife is protected by the guard plate C which includes an arcuate edged portion C¹ adapted to penetrate within the forward recess B³ of the knife. It will be observed that the axis of the knife preferably lies in a horizontal plane but is tilted slightly from perpendicularity in relation to the guard plate C, in order to bring the cutting arc of the knife into or beyond the plane of the guard plate.

D generally indicates a rear guard member associated with the hub D¹ in which rotates the knife shaft B¹. In some circumstances it is preferable to recess the rear of the knife

as at B⁴ in order to receive the edge or periphery D² of the guard D.

E generally indicates a gauge plate with the arcuate edge E¹ generally concentric with and opposed to the cutting arc of the knife. Any means may be employed to move the gauge plate E toward and away from the plane of the knife and laterally toward and away from the edge of the knife. Referring to the dotted line position of the gauge plate in Figure 1, I illustrate the preferred movement of the gauge plate which is along a path inclined to the cutting plane of the knife in such fashion that recession of the gauge plate widens the throat between gauge plate and knife in two directions. However the invention herein shown is operable with gauge plates which are drawn directly back from the cutting plane, as indicated in the full and dotted line positions in Figure 3.

Mounted on the gauge plate E I indicate a guard member G. The guard may be formed integrally with the gauge plate or it may be secured thereto as by the screws G¹. It is arcuate in form and includes a portion G² extending laterally toward the knife from the gauge plate and conforming generally to the contour of the knife. It will be observed, from Figures 1 and 3, that the guard member overlies or overlaps the rear of the exposed arc of the knife in such fashion as to make it impossible for the finger of the operator to engage the knife edge along the cutting arc. The size of the member G² is such that it efficiently exercises its guarding function even when the gauge plate is withdrawn to a maximum depth.

When the gauge plate is closely set the guard portion G² may extend to or almost to the edge D² of the guard D. However there is sufficient space between the knife and the member G² for the slices to escape after they are cut. An efficient method of using the device is for the operator to take the slices in his fingers as they are discharged and lay them either on the receiving tray generally indicated as H or otherwise dispose of them. However the tray H is in position to receive the slices if they are permitted to fall.

In order further to protect the fingers of

the operator about the lower arc of the knife, whether from the front or the rear I provide an additional guard member herein shown as mounted on the gauge plate. It includes the body or base portion J adjustably mounted on the gauge plate as by the slots J¹ and securing screws J². Projecting from it is the arcuate guard portion proper J³ which lies in the general plane of the knife and closely adjacent the cutting edge in such fashion that the finger of the operator cannot engage the cutting edge. The guard may be set close to the edge, as by the adjusting means above indicated and since it is positioned below the cutting arc proper, there is no interference with the operation of the device.

It will be understood that any suitable meat carriage, herein generally indicated as K, may be moved across the face of the gauge plate and guard plate as on the tracks K¹ K². It will be observed that the level of the guard J³ is below the bottom of the meat carriage and that therefore it does not interfere with the operation of the knife.

Note that in the form of Figures 2 and 4 the gauge plate E is slotted to receive the securing screws of the body portion J of the guard member. In Figures 5 and 6 I illustrate a variant form in which the body portion L of the guard, slotted for adjustment as at L¹, is secured to the front of the gauge plate as by the adjusting screws L². The arcuate portion L³ is opposed to the cutting edge of the knife in like fashion as the member J³.

It will be realized that whereas I have described and shown a practical and operative device, nevertheless many changes might be made in the size, shape, number and disposition of parts without departing from the spirit of my invention. I therefore wish my description and drawings to be taken as in a broad sense illustrative and diagrammatic rather than as limiting me to my specific showing.

The use and operation of my invention are as follows:

In employing a slicing machine of the type herein shown there is constant risk of damage to the operator, of cut or severed fingers, unless the edge of the knife is properly protected. I have provided a peculiarly complete shielding of the cutting edge. Referring for example to Figures 1 and 2 well over half of the periphery of the knife is entirely enclosed. The guard member G² overlies and entirely protects most of the remaining exposed arc, including the rear of the knife along the cutting arc proper. The members J³ or L³ may be adjusted so closely to the remaining of the exposed cutting edge, over the work receiving tray H, as to make it impossible for the operator to engage the cutting edge with his finger. This leaves exposed only the actual cutting arc of the knife, the arc extending from the top to the bottom

of the gauge plate on the front of the machine. Thus except for the cutting arc actually necessary to engage the material to be cut, the entire edge of the knife is protected and the result is a slicing machine as safe as its functions can permit it to be. The edge is entirely protected from the rear and protected except along the actual cutting arc in the front.

I claim:

1. In a slicing machine which includes a rotary knife, a carriage and means for conveying it across the face of the knife and a gauge plate generally parallel with the path of movement of the carriage, a guard member associated with said gauge plate and overlying the rear face of the knife at all positions of the gauge plate.

2. In a slicing machine which includes a rotary knife, a carriage and means for conveying it across the face of the knife and a gauge plate generally parallel with the path of movement of the carriage, a guard member associated with said gauge plate, and extending laterally therefrom toward the opposed knife edge and overlying the rear face of the knife at all positions of the gauge plate.

3. In a slicing machine which includes a rotary knife, a carriage and means for conveying it across the face of the knife and a gauge plate generally parallel with the path of movement of the carriage, a guard member extending laterally and rearwardly from the edge of the gauge plate opposed to the knife edge.

4. In a slicing machine which includes a rotary knife, a carriage and means for conveying it across the face of the knife and a gauge plate generally parallel with the path of movement of the carriage, a guard member extending laterally and rearwardly from the edge of the gauge plate opposed to the knife edge, and overlying the rear face of the cutting arc of the knife.

5. In a slicing machine which includes a rotary knife, a carriage and means for conveying it across the face of the knife and a gauge plate generally parallel with the path of movement of the carriage, a guard member extending laterally and rearwardly from the edge of the gauge plate opposed to the knife edge, and overlying the rear face of the cutting arc of the knife, said guard terminating in an arcuate edge generally concentric with the knife axis.

6. In a slicing machine which includes a rotary knife, a carriage and means for conveying it across the fence of the knife and a gauge plate generally parallel with the path of movement of the carriage, a guard for the rear of said knife, said guard terminating in an arcuate edge portion closely approaching the rear face of the knife about an arc lying within the periphery of the knife, and a guard member, associated with said gauge plate and

projecting laterally therefrom and overlying that portion of the rear face of the cutting arc of the knife which is exposed by said first mentioned guard.

5 7. In a slicing machine which includes a rotary knife, a carriage and means for conveying it across the face of the knife and a gauge plate generally parallel with the path of movement of the carriage, a guard for the rear of said knife, said guard terminating in an arcuate edge portion closely approaching the rear face of the knife about an arc lying within the periphery of the knife, and a guard member, associated with said gauge 10 plate and projecting laterally therefrom and overlying that portion of the rear face of the cutting arc of the knife which is exposed by said first mentioned guard, said last mentioned guard member lying in a plane generally 15 parallel with the plane of the opposed knife surface.

8. In a slicing machine which includes a rotary knife, a carriage and means for conveying it across the face of the knife and a gauge plate generally parallel with the path of movement of the carriage, a guard member extending laterally and rearwardly from the edge of the gauge plate opposed to the knife edge, and overlying the rear face of, 20 the cutting arc of the knife, said guard member being generally uniformly spaced from the opposed rear surface of the knife.

9. In a slicing machine having a rotary knife and means for rotating it, a gauge plate, 25 a carriage and means for guiding said carriage across said gauge plate and past the cutting edge of the knife, a slice receiving member adjacent and to the rear of the cutting arc of the knife and a guard for the edge 30 of the knife adjacent and just above said slice receiving member, said guard being positioned upon and movable with said gauge plate and extending about the edge of the knife adjacent but beneath the cutting arc.

40 45. 10. In a slicing machine having a rotary knife and means for rotating it, a gauge plate, a carriage and means for guiding said carriage across said gauge plate and past the cutting edge of the knife, a slice receiving member adjacent and to the rear of the cutting 45 arc of the knife and a guard for the edge of the knife adjacent and just above said slice receiving member, said guard being positioned upon and movable with said gauge

50 55. plate and extending about the edge of the knife adjacent but beneath the cutting arc, and an additional guard means mounted upon said gauge plate, said guard means being adapted to overlie the rear face of the knife 55 at all positions of the gauge plate and being adapted to mask from the rear the actual cutting arc of the knife.

60 65. 11. In a slicing machine having a rotary knife and means for rotating it, a gauge plate, a carriage and means for guiding said car-

riage across said gauge plate and past the cutting edge of the knife, a slice receiving member adjacent and to the rear of the cutting arc of the knife, a guard positioned upon said gauge plate, adapted to guard the cutting arc of the knife from the rear, at all positions of the gauge plate and additional guard means adapted to guard the edge of the knife adjacent but beneath the cutting arc, said guard means extending across the effective 70 receiving surface of the slice receiving member.

75 12. The structure of claim 11 characterized by the employment of a cover member positioned above the knife and guarding the edge 80 of the knife above said first mentioned guard for the cutting arc.

85 13. In a slicing machine having a rotary knife and means for rotating it, a gauge plate, a carriage and means for guiding said carriage across said gauge plate and past the cutting edge of the knife, a slice receiving member adjacent and to the rear of the cutting arc of the knife, a guard positioned upon said gauge plate, adapted to guard the cutting arc of the knife from the rear, at all 90 positions of the gauge plate and additional guard means adapted to guard the edge of the knife adjacent but above the cutting arc.

95 Signed at Indianapolis, county of Marion and State of Indiana, this 5th day of June 1928.

WILLIAM J. CAMPBELL.
